UNITED STATES PATENT OFFICE.

ERIK GUSTAF FRYKBERG, OF NEWARK, NEW JERSEY.

STEAM-ENGINE.

SPECIFICATION forming part of Letters Patent No. 254,125, dated February 28, 1882.

Application filed October 1, 1881. (No model.)

To all whom it may concern:

Be it known that I, ERIK GUSTAF FRYKBERG, a subject of the King of Sweden, residing in the city of Newark, county of Essex, 5 and State of New Jersey, have invented certain new and useful Improvements in Steam-Engines, fully described and represented in the following specification and the accompanying drawing, forming a part of the same.

My invention relates to an improvement in steam-engines, and it consists in an improved apparatus for saving heat and water by retaining the uncondensed steam in the cylinder or its passages after each stroke, and returning 15 the water of condensation to the boiler by means of a force-pump.

In the drawing annexed there is represented a steam-engine constructed with my improvements, A being the steam-cylinder; B, the bed; C, the crank-shaft; D, the crank; E, the fly-wheel; F, the crank-shaft bearings; G, the connecting-rod; H, the slides; I, the piston-rod; J, the cross-head; K, the piston; L, the steam-chest; M, the condensed-water pump; N, the boiler; O, the boiler-feed pump; P, the eccentric on shaft C, for operating the same; R, the eccentric for operating the steam slide-valve and the pump M, and S a stop-cock in steam-pipe T, connecting the boiler N to the 25 chest L.

a are the steam-ports leading from the ends of the cylinder to the valve-seat in chest L. b is the valve, of any suitable construction, adapted to cut off the steam at a desired point. c is the exhaust-passage in the valve-seat. 30 d is the valve-rod, and e its connection with eccentric R.

The pumps M and O are provided with suitable valve-chambers, f, and delivery-pipes to 40 the boiler, provided, if required, with check-valves g. The pump O is supplied with water from any source by pipe h, and the condensed-water pump M is connected by pipe i with the exhaust-passage c, or to separate openings, Q, 45 at each end of the cylinder A by pipes V V.

U is the rod connecting pump O with its eccentric.

The operation of my engine is based upon the facts that when steam is performing work 50 in a steam-engine the heat contained therein is converted into power, causing a corresponding decrease of pressure of such steam. Con-

sequently it requires a less amount of power to compress the steam to its original pressure after working expansively in a steam-cylinder 55 than it exerted during the performance of such work; and if a certain amount of steam is admitted into a steam-engine cylinder from which neither heat nor steam can escape, and work is applied to the piston, causing a compression of the steam into a smaller volume, thereby increasing its pressure, such work is stored up and available, as it would be if used in bending a steel spring. My method, therefore, of saving the latent heat in the steam operating 60 a steam-engine is to operate the same to any degree of expansion—say four times—and to form the space or clearance in the ends of the cylinder or its passages of sufficient capacity 65 to contain the steam after compression by the 70 reverse movement of the piston after the expansion of such steam. With such construction I permit no exhausting of the steam after 75 each stroke, but withdraw the condensed steam or water by a pump, M, and force the same into the boiler or steam-generator, supplying the loss of steam so condensed at each stroke by live steam from the boiler.

The action of the steam during one stroke of my engine will be best understood by assuming an engine of certain proportions operating under a given pressure. It is obvious that the back-pressure upon the piston must increase up to the end of the stroke in an engine having no exhaust, while the operative pressure 85 upon the piston must decrease in a cylinder using steam expansively. The movement of the piston must therefore be maintained either by a fly-wheel or its equivalent absorbing the power exerted by the engine. The power given 90 out by the steam is thereby distributed throughout the stroke, as required to maintain the operation continuously. I will suppose that into a cylinder of four cubic feet capacity one cubic foot of steam is admitted by a cut-off 95 valve operating to close the induction-port at one-quarter stroke, the steam being introduced at sixty pounds pressure and expanded during the remainder of the stroke. Under such conditions it will be found that the cubic foot of 100 steam will lose a certain part of its weight during the performance of the work, that portion being converted into water; and that if compressed in the cylinder, by the return of the

piston, to its initial pressure of sixty pounds, it will retain only a part of its original weight. The steam converted into water may be readily withdrawn by a pump and returned to the 5 generator N. The steam and water remaining contain the heat not converted into work, and by my method of operation such heat is utilized by pumping the condensed water back to the boiler directly from the cylinder or its 10 passages, all the heat contained therein being preserved from loss, excepting such as may be dissipated by absorption and radiation from the conducting-pipes.

By constructing the cylinder with a clearance of certain capacity the steam used may 15 be compressed by the piston to the desired density before the steam-ports are opened to admit a fresh supply at the beginning of each stroke.

20 To move the piston under the back-pressure a portion of the power stored in the fly-wheel in the earlier part of the stroke would need to be expended; but the reaction of the same steam in its second expansion would again operate 25 efficiently in starting the piston upon its advance movement, and the available force for driving the engine would be that due to the consumption of the steam condensed into water.

From the above it is obvious that it requires 30 an engine of larger size to develop a given power than engines now in use; but such increase of size and consequent cost of the engine is considerably more than repaid by diminution of the boiler or steam-generator, while 35 the saving secured by my mode of operation is permanent and constant in its benefit, and practically amounts to the saving of all the heat in the steam retained in the cylinder, besides preventing the loss of a large amount of 40 water. As this saving results from my improved method of operating the engine, the method described can be employed in any suitable engine by shortening the stroke of the piston, or supplying new heads chambered out to

afford the necessary space to avoid compressing the steam above the boiler-pressure. 45

The addition of a small pump to return the condensed water to the generator, and the application of a valve adapted to operate the steam expansively, would then fit the engine 50 for use by my method, the exhaust passage or outlet being permanently closed.

A feed-pump, as at O in the drawing, would of course be required to supply the loss of steam or water by leakage, &c., as in other engines, and all the precautions taken which can be employed to prevent the loss of heat by radiation. 55

My invention is only applicable to engines using steam expansively, for the reason that 60 when the steam is taken into the cylinder during the whole of the stroke there is no such diminution of bulk or temperature possible as I have described, because of the open communication between the cylinder and the boiler, the latter supplying the loss of heat as rapidly as it is converted into work, and the cylinder at the close of the stroke containing steam of undiminished temperature.

Having thus fully described my invention, I 70 claim as follows:

The combination of a steam-cylinder of sufficient clearance, supplied with a valve mechanism, for operating the steam expansively, induction-ports for the admission of live steam 75 to the cylinder, and passages for the escape of water of condensation from the cylinder, and a pump connected with such water-passages, suitably connected and operated to return such water to the steam-generator, substantially as 80 and for the purpose set forth.

In testimony whereof I have hereunto set my hand in the presence of two subscribing witnesses.

E. G. FRYKBERG.
